[57] CLAIM

The ornamental design for a hairbow and barrette holder, as shown and described.

DESCRIPTION

FIG. 1 is an environmental view of a hairbow and barrette holder showing my new design;

FIG. 2 is a front elevational view thereof;

FIG. 3 is a rear elevational view thereof;

FIG. 4 is a top perspective view thereof;

FIG. 5 is a left side elevational view with the right side being a mirror image thereof;

FIG. 6 is an environmental view of a second embodiment of a hairbow and barrette holder;

FIG. 7 is a front elevational view thereof;

FIG. 8 is a rear elevational view thereof;

FIG. 9 is a top perspective view thereof; and,

FIG. 10 is a left side elevational view with the right side being a mirror image thereof.

The broken line showings of the bows on the braids and the lace on the hat in FIGS. 1 and 6 are for illustrative purposes only and forms no part of the claimed design.

The braid element is shown broken-away in the views to indicate indeterminate length.
